UNITED STATES PATENT OFFICE

ABRAHAM M. BABITCH, OF FLINT, MICHIGAN, ASSIGNOR TO A C SPARK PLUG COMPANY, OF FLINT, MICHIGAN, A COMPANY OF MICHIGAN

FUEL PUMP OPERATING PART

Application filed August 2, 1928. Serial No. 297,021.

As may be understood from the above title, this invention relates to fuel pumps such as are now employed upon automotive vehicles, and elsewhere in connection with internal 5 combustion engines; and it is an especial object of this improvement to provide simple and effective intermediate means for a thrust-refusing transmission of motion from a pump actuating element, such as an oscillating lever, or the like, to a reciprocable pumping element, such as a diaphragm,—the stroke imparted thereto being dependent upon the pressure built up within a pump chamber.

10 Although the present invention is herein described with particular reference to a diaphragm pump of the general character described and claimed in my pending application, Ser. No. 123,370, filed July 19, 1926; 15 it should be understood that the principles of this invention are believed to be applicable to other reciprocatory pumps in which provision is made for the use of resilient means to effect an expulsion stroke of a pumping 20 element, the intake stroke thereof being positively effected but variable in length.

25 Other objects of this invention, all forms of which involve the use of either a sectional actuating element or sectional intermediate 30 means between an actuating element and a part to which a reciprocatory pumping element, such as a diaphragm, is connected (the mentioned sections being provided with resilient means tending to flex a joint therebetween, and/or tending to hold one section of 35 an actuating element in engagement with a cam, or the like) may be best appreciated from the following description of illustrative embodiments of said invention, taken in connection with the appended claims and the 40 accompanying drawing:

Fig. 1 may be referred to as a substantially median vertical section through a pump including an embodiment of this invention,—not all features therein shown being necessarily included in any one pump.

45 Fig. 2 is an enlarged detail view, comparable with a lower central portion of Fig. 1, 50 but separately illustrating one simple and

advantageous embodiment of this invention.

Fig. 3 is a view similar to Fig. 2, but separately showing an alternative single embodiment of this invention.

Fig. 4 is a view comparable with Fig. 1, but 55 less complete and illustrative of a further modification in which separate resilient means may advantageously be employed constantly to press one end of an actuating lever into engagement with a cam, or the like. 60

Referring first to Figs. 1 and 2 as showing conventional parts of a fuel pump of the general character disclosed in my mentioned prior application, a main structural element in the form of a body casting 1 and a subsidiary structural element in the form of a cover casting 2 are shown as cooperating in the retention of a reciprocatory pumping element in the form of a flexible diaphragm 3,—this being conditionally effective to vary 70 the cubic contents of a pump chamber 4, shown as provided in the cover casting 2.

The cover casting may be provided not only with an inlet passage 5 and an outlet passage 6, 7 (the latter being shown as valved 75 at 8) but also with an inlet valve and means for supporting a filter, not shown.

An oscillable actuating element in the form of a lever comprising arms or sections 9 and 9', said sections being either integral or separate, may be pivoted to the casting 1, as at 10; and the outer section 9' thereof may be adapted continuously to engage a reciprocatory or rotatively driven element such as a cam 11 upon a shaft 12,—any suitable means being employed to effect the result last referred to.

Coming now to the novel features of the new combination upon which protection is herein sought, assuming some suitable handling element (such as, for example, a so-called diaphragm stem 13) to be suitably attached to a pressure-responsive pumping element such as the diaphragm 3, and assuming resilient means such as a compression spring 14 to be employed in initially imparting expulsion strokes to said pumping element, thrust-refusing means such as links or sections 15, 16, centrally pivoted to one another at 17 may be respectively pivoted at 100

18 at one distal end to the diaphragm stem 13 and at the other distal end 19 to the inner section 9 of the mentioned actuated element; and, in order to predispose the mentioned sections 15, 16 of the described intermediate means toward a flexed relationship, such as that shown in full lines in Figs. 1 and 2, resilient means such as a spring 20 (shown as wound about the pivots 17, 18 and 19) and/or 10 a tension spring 21 (connected with one of said links or with the pivot 17 and with a fixed element such as a so-called plug 22, shown as adjustably inserted in the casting 1) may be employed.

15 In Fig. 2, the actuating element pivoted at 10 is shown as formed in a single piece which may be regarded as comprising arms or sections 9a and 9a'; and either of the mentioned springs or the two spring together may be 20 of sufficient power not only to bias the described intermediate means, comprising sections 15 and 16, toward a flexed relationship, preventing a parallel relationship therebetween, but also incidentally to hold the section 25 9' (or 9a') of the described actuating means against the cam 11 or its equivalent; but, in addition to or instead of the mentioned spring or springs, use may be made of resilient means associated with a joint between the sections of a sectional actuating element, one suitable construction for the purpose here referred to being separately illustrated in Fig. 3.

In Fig. 3, as also in Fig. 1, the sections 9 35 and 9' are shown as separately movable upon the pivot pin 10; said pin is here shown as surrounded by coils of a spring 23; oppositely tending portions 24 and 25 of this spring are shown as so engaging the respective sections 9 and 9' as to flex the joint therebetween; and the respective sections mentioned are provided with means (as, inclined opposable faces 26, 26' and 27, 27') effective to 40 limit relative rotation between the sections 45 9 and 9' in opposition to the tendency of the spring 23.

Using the construction last referred to, the inner actuating element section 9 may be secured to an intermediate element such as a 50 link section 15-16; an end 28 of the spring 23 may optionally so engage the casting 1 as to press the section 9' always toward the cam 11; and/or, if the spring 23 is of sufficient power, the previously mentioned springs can be dispensed with. The thrust-refusing construction last described may be relied upon to 55 impart intake strokes of a diaphragm 3, or its equivalent, although obviously incapable of imparting expulsion strokes thereto.

60 As above implied, any one or two or all three of the described springs may be concurrently employed; but there is suggested in Fig. 4 an alternative construction in which, although resilient means may be employed to 65 prevent a noise-producing contact between

metallic parts and/or to predispose or bias sections of a thrust-refusing intermediate means toward relative flexure, no metallic springs need be interposed between the relatively movable sections.

70

The figure last referred to shows a modified form of linkage in which two separate sets of links are used, each or either of which may be similar to the links or sections shown in Fig. 1. The substantially parallel links 53 and 54 are not directly connected but are secured upon the same side of flattened end portions of the diaphragm stem 55 and an actuating element in the form of a lever or rocker arm comprising a section 56; and the links 57 and 58 are placed upon the other side of said flattened end portions, pivot pins 59, 60, 61 and 62 being employed as shown. Optionally, cushioning or compression resistant means such as leather or other inserts 63 may be so interposed as to prevent noisy contact between parallel links.

75

The construction here referred to is such that neither of the intermediate pins 61, 62 can ever reach the same vertical line with the pivot pins 59, 60, the result being that the links will always be predisposed toward a flexing movement and incapable of transmitting a thrust to pumping element 3 or its equivalent, although conditionally effective to impart intake strokes thereto whenever pressure within the chamber 4 is insufficient to hold said pumping element down. It will be obvious, however, that unless more powerful resilient means than the suggested inserts 63 are interposed between the described pairs of links or their pivots 61 and 62 separate resilient means (such as, for example, a compression spring, which may be confined between cups 64 and 65) may advantageously be employed (as described in the mentioned prior application) resiliently to hold a section 56' of the actuating lever against a suitable cam, or the like.

80

100 Although the above description includes several alternative embodiments of this invention, these being capable of either conjoint or separate use, it will be obvious that additional modifications thereof might easily be devised, without departure from the spirit and scope of the invention, and as the same is indicated above and in the following claims.

85

110 I claim:

1. In means for imparting a variable stroke 115 to a pumping element conditionally reciprocable in a pump chamber; a handling element attached to said reciprocable element; actuating means comprising a section which is reciprocable by a cam; and intermediate means pivotally connected with a section of 120 said actuating means and with said handling element,—one of the mentioned means comprising sections which are connected by a 125 pivotal joint and are provided with resilient means tending to prevent parallelism of said 130

sections and to prevent transmission of a thrust therethrough.

2. An organization as defined in claim 1 in which said joint comprises a pivot pin and 5 said resilient means comprises a spring which so acts on said pin as to tend to flex said joint.

3. An organization as defined in claim 1 in which said resilient means is effective both to prevent transmission of a thrust through said 10 intermediate means and to hold a section of said actuating means against said cam.

In testimony whereof I affix my signature.
ABRAHAM M. BABITCH.
